UNITED STATES PATENT OFFICE.

ATTIE WRIGHT, OF MARSHFIELD, WISCONSIN.

FLOUR BIN.

Application filed April 30, 1923. Serial No. 635,750.

To all whom it may concern:

Be it known that ATTIE WRIGHT, a citizen of the United States, residing at Marshfield, in the county of Wood and State of Wisconsin, has invented certain new and useful Improvements in Flour Bins, of which the following is a specification.

This invention has reference to flour bins and its object is to provide a multiple flour bin for containing a plurality of kinds of materials to be distributed to various points for use.

In accordance with the invention there is provided an upright bin rotatable about an intermediate axis and of generally circular cross section with one side flattened to provide for the housing of the bin under the projecting side of a counter or cover so that the bin may be completely protected from contamination from above and yet all parts of the bin may be accessible so the contents of various compartments in the bin may be readily reached.

The bin is divided into a plurality of compartments by partitions fitting into grooves admitting of the ready removal of the slides for cleaning purposes.

The invention will be best understood from a consideration of the following detailed description taken in connection with the accompanying drawings forming part of this specification with the understanding, however, that the invention is not confined to any strict conformity with the showing in the drawings but may be changed and modified so long as such changes and modifications mark no material departure from the salient features of the invention as expressed in the appended claim.

40 In the drawings:

Figure 1 is an elevation with some parts in section showing the rotatable member of the bin located between a floor member and a cover member;

45 Figure 2 is a vertical section through the bin as disclosed in full lines in Figure 1;

Figure 3 is a section on the line 3-3 of Figure 1;

50 Figure 4 is a fragmentary perspective view of a portion of the bin; and

Figure 5 is a perspective view of a portion of a pivot on which the bin is mounted.

Referring to the drawings, there is shown a counter 1 which may be indicative of a shelf designed to override and protect the bin from contamination and between the

counter 1 and a flooring 2 there extends an upright shaft 3 about the axis of which a bin structure 4 may revolve.

The bin 4 is of generally circular form except that at one side there is provided a flat side section 5. Extending from the shaft 3 to one side of the main body 4 of the bin there is a partition 6 and extending from the other side of the shaft 3 to the opposite side of the cylindrical part of the bin 4 there is another partition 7 corresponding generally to the partition 6. Intermediate of the partitions 6 and 7 is a third partition 8 disposed radially to the axis of rotation of the bin 4.

The shaft 3 is provided with a suitable number of longitudinal grooves 9 and on the inner face of the bin 4 are return loops 10 to receive the adjacent ends of the partitions 6 and 7 and 8 into which groove the corresponding sides of the partitions 6, 7 and 8 slide.

The opposite ends of the shaft or pivot 3 are pointed as shown at 11 and are seated in sockets 12 made fast to the cover 1 and floor 2, respectively. In the upper end of the shaft 3 there is enclosed a compression spring 13 bearing against the pivot end 14 and holding the bin 4 in place. The upper end of the bin 4 is closed by a cap 15 holding the shaft 3 central to the bin 4 and permitting the displacement of the cap whenever desired.

The bin 4 is adapted to receive a plurality of kinds of contents. When it is desired to obtain access to any one of the compartments of the bin, the desired compartment is opened by bringing it in such relation to the peripheral portion of the bin that such portion of the container may be brought under the overhanging part of the counter, thus exposing the interior of the bin to access and the bin may be turned from place to place about the axis of the shaft 3 until the various compartments of the bin are presented to view and the contents of the exposed compartment may be reached, especially when the cover 15 is removed.

When the upper portion of the bin is pulled or forced from under the counter the pivot end 14 slips out of the bearing which is applied to the underside of the counter. By reference to figure 2 of the drawing it will be seen that the pivot end or member 14 is supported by a spring 13 at the upper end of the shaft 3. Therefore, the pivot mem-

ber may move longitudinally with relation to the shaft. When the bin is moved to an inclined position the cover 15 may be lifted off of the upper end of the bin and if necessary the pivot member 14 may be depressed to permit of free removal of the cover from the bin. When the material is being dispensed from the bin the bin is stationary and is in an inclined position upon the floor, 10 it being supported at its center by the lower end of the shaft and at its edge by the lower edge of the flattened portion which is provided at the side of the body of the bin. Therefore, during the operation of dispensing 15 the material from the bin the body thereof is held at a steady position upon the floor.

The edge portion of the counter is shown in dotted lines in Figure 3, from which it

can be ascertained that in tilted position, 20 the contents of the bin may be removed.

What is claimed is:

A bin adapted to be supported between bearings applied to fixed objects comprising a body of general cylindrical form and having a flat side section which extends from end to end of the body, a cover for the body, the shaft section fixed centrally in the body and adapted to engage in one of the bearings, a pivot member alined with the shaft 25 and passing through the cover and adapted to engage in the other bearing, and a spring interposed between the shaft and the pivot member. 30

In testimony whereof I affix my signature. 35

ATTIE WRIGHT.
